MANUFACTURE OF SHOES

Alfred W. Donovan and Alfred F. Donovan,
Quincy, Mass., assignors to E. T. Wright & Company, Inc., Rockland, Mass., a corporation of Massachusetts

Application January 26, 1940, Serial No. 315,638

4 Claims. (Cl. 36—71)

The invention set forth in this application relates to an improvement in the manufacture of shoes and more particularly to the manufacture of a bottom structure or "chassis" which comprises briefly an insole having a depression in its bottom surface of predetermined contour and dimension and a complementary elevation in the top surface, a metatarsal pad, of one or more elements, mounted in such depression, and a shank iron fixed to the bottom surface of the insole, the head of which shank iron has a depression in which said pad is received and exerts a supporting pressure upon the metatarsal arch of the foot in a forward upward direction, and to the structure and formation of such metatarsal pad, all as hereinafter set forth and claimed.

The purpose of such a bottom structure is to provide, in the shoe with which it is assembled, a support for the metatarsal arch of the wearer. The support exerts a forwardly and upwardly inclined pressure upon that arch, such pressure being transmitted from the outer sole of the shoe through the shank iron and pad to the insole. This direction of the line of pressure is due to the fact that the point at which the shank iron acts upon the pad is appreciably to the rear of the point at which the pad acts upon the insole.

A further feature of this invention resides in the form of the metatarsal pad which insures a direct transmission of the pressure because the depression in the shank head and the depression in the insole are completely filled and any gaps or spaces that are left or may result from wearing stresses are filled by the material of the pad so that no breaking down of the pad will occur. Such gaps or spaces often arise at the rear wall of the depression in the insole due to the forward and downward pressure exerted by the foot at that wall. In accordance with this invention that wall is given a definite slope rearwardly so that the bottom of the foot will slide freely thereover without meeting any appreciable resistance. Moreover, the edge of the pad in contact with that wall is tapered and extends beyond the portion of the pad in the shank iron depression so that it is flexible, and while the wall may be subjected to forward pressure, the normal resistance of the wall, due to its angular construction to such pressure, will be yieldably supplemented by the pad.

These and other objects and features of the invention will appear from a consideration of the

following description and of the drawings which form a part thereof and in which:

Fig. 1 is a bottom plan view of a completed bottom structure embodying this invention;

Fig. 2 is a bottom plan view of a last with which the bottom structure is assembled;

Fig. 3 is a sectional view of such last taken along the section line 3—3 in Fig. 2;

Fig. 4 is a top plan view of the insole of the bottom structure;

Fig. 5 is a sectional view taken along the line 5—5 in Fig. 4;

Fig. 6 is a bottom plan view of the insole shown in Fig. 4;

Fig. 7 is an enlarged sectional view taken along the section line 7—7 in Fig. 1 of a bottom structure assembled with the outsole;

Fig. 8 is a top plan view of the shank iron of such bottom structure;

Fig. 9 is a sectional view taken along the section line 9—9 in Fig. 8;

Figs. 10 and 11 are perspective views of the metatarsal pad of such bottom structure;

Fig. 12 is a perspective view of such pad taken from the section line 12—12 in Fig. 10;

Fig. 13 is an enlarged view of that portion of the bottom structure and outsole within the rectangle 13 in Fig. 7;

Figs. 14 and 15 are bottom plan views of the bottom structure before and after the shank iron is positioned; and

Fig. 16 is a view similar to Fig. 12 of a moulded metatarsal pad.

The bottom structure or "chassis" 20 shown in the drawings includes an insole 21, a shank iron 22, a metatarsal pad 23 between insole and shank iron at the ball portion of the bottom structure, and a reinforce sheet or layer of fabric 24 covering the insole and pad and on which the shank iron rests.

At the ball portion of the insole 21 is formed, usually by moulding, an integral elevation 25 at the upper surface and a corresponding depression 26 at the under surface. The elevation 25 is segmental in form, having a curved front edge 27 and substantially straight rear edges 28 and 29 which intersect at 30. The rear walls 31 and 32 of the elevation extend forwardly and upwardly from the edges 28 and 29 to meet the arcuate front wall 33 which extends rearwardly and upwardly. The walls 31 and 32 define a dihedral angle 34 and with the front wall 33 define dihedral angles 35 and 36. Thus, the elevation may be considered as possessing the form of a shallow pyramid having a segmental

- base and an apex 37. The inclinations of the walls 31, 32 and 33 are so gradual that they do not materially raise the upper surface of the insole i. e. to such an extent as to affect adversely the normal movement of the foot into and out of the shoe. In addition to the elevation 25, the upper face of the insole is also provided with a depression 38 extending longitudinally from the point 39 toward the heel seat. 5
- 10 Since the depression 26 is complementary to the elevation 25 and corresponds in all respects thereto, the cognate elements will be designated by the same reference numerals without further description.
- 15 The elevation 25 is so formed and positioned that it supports the metatarsal arch of the foot of the wearer. This is determined by the distance 39 from the rear end of the insole to the point 30 at which the edges 28 and 29 intersect. 20
- 20 The metatarsal pad 23 comprises an upper portion 40 and a lower portion 41. These portions may be separate elements permanently joined together as shown in Fig. 12, or the pad may be an integral unit as shown in Fig. 16. Both portions 40 and 41 are segmental in contour. The outer surface of the portion 40 is formed by inclined planes, the rear walls 42 and 43 being positioned at an angle to each other and the front wall 44 having an arcuate forward edge 25
- 30 45. The joinder of these three walls is defined by the edges 46 and 47 which meet at the apex 48 of the upper portion. The walls 42 and 43 meet along the edge 49 which leads downwardly and rearwardly from the apex 48 to point 50. 35
- 35 The outer surface of the portion 41 is also formed by inclined planes, the rear walls 52 and 53 being positioned at an angle to each other and the front wall 54 having an arcuate forward edge 55. The joinder of these three walls is defined by the 40
- 40 edges 56 and 57 which meet at the apex 58 of the lower section. The walls 52 and 53 meet along the edge 59 which leads downwardly and forwardly from the apex 58. It will be noted that the upper portion 40 is larger than the 45
- 45 lower portion 41 and that the portions are so formed and positioned that the edges 45 and 55 are in contact, and that the walls 52 and 53 are inward of the rear edges of the walls 42 and 43, thus exposing a plane surface 60 of the upper portion. 50
- 50 The pad 23 is seated in the depression 26 and held therein by any suitable means such as adhesive or cement. The upper portion 40 of the pad 23 is so formed and of such dimensions that the walls 42, 43 and 44 thereof register with the walls 31, 32 and 33 of the depression 26, the apex 48 being in contact with the apex 37 and the plane surface 60 forming an extension of the under surface of the insole. In addition to providing the insole with the elevation 25 and its complementary depression 26 the edge may be channeled and the under surface cut along the line 65 to provide flaps which turned up coact to form a sewing rib 66, in accordance with the old and well known practice. 60
- 65 After the pad 23 has been seated in the depression 26 (see Fig. 14) a sheet or layer 24 of fabric or the like is applied to the under surface of the forepart and shank of the insole thus covering the pad 23 and forming a lining for the inner edge of the sewing rib 66 (see Fig. 15). The sheet 24 is secured to the walls 52, 53 and 54 of the lower portion and also to the plane surface 60 of the upper portion (see Figs. 7 and 13). 70
- 75 The wall 54 of the pad and that portion of the

sheet 24 which covers it are provided with indentations which serve as positioning recesses 67 for the shank iron in the manner to be described below.

The insole with the pad 23 and sheet 24 is now assembled with a last preparatory to the pulling-over operation. The last 70 (Figs. 2 and 3) is provided with a segmental depression 71 having rear walls 72 and 73 and front wall 74. These walls are so formed that the walls of the 10 elevation 25 register therewith. Leading from the point 75 at which the edges 76 and 77 meet and extending longitudinally toward the heel is an elevation 78. The point 75 is a distance 79 from the rear end of the last which is equal to 15 the distance 39 between the point 30 of the elevation and the rear end of the insole. Thus, by merely laying the insole on the bottom of the last with the elevation 25 in register with the depression 71 and the depression 39 in register 20 with the elevation 78, the insole is accurately positioned transversely and longitudinally of the last. Since the slope of the walls 31 and 32 of the insole and the walls 72 and 73 of the last with which they register is quite considerable, e. g., of 25 an order of 30°, an abutment is provided adequate to resist rearward movement of the insole on the last during the pulling-over movement.

Since the pad 23 had been seated in the depression 26 before the insole was assembled with 30 the last, the depression 71 is, as pointed out above, accurately formed to receive the elevation 25 without allowing any appreciable play. Heretofore, it has been the practice in the manufacture of shoes having a metatarsal arch support to assemble the insole with the last and thereafter to mount the metatarsal pad in the depression of the insole. In order to insure a proper mounting and locating of the pad, pressure is required which is transmitted to the walls 40 of the depression. The depression in the last was consequently made somewhat larger than the elevation of the insole to allow sufficient play so that the insole elevation walls may yield in response to such pressure and the material forming such 45 insole be not injured thereby.

The shank iron 22 is now mounted upon the insole. Such iron includes a triangularly formed depression 80 in the upper face at the head of the iron and a groove 81 extending longitudinally 50 from the apex 82 of the depression toward the rear end and is provided at the head end with upturned prongs 83. The shank iron is located properly upon the insole by inserting the prongs 83 in the recesses 67 and placing the groove 81 55 over the longitudinal rib formed at the under surface of the insole by the moulding of the depression 38 therein. Nails through the holes 84 hold the shank iron in this position. The depression 80 in the head of the shank iron is so 60 formed that the iron, when properly mounted on the insole, bears against the walls 52, 53 and 54 of the lower portion of the pad 23 and the apex 58 of that portion rests in the apex 82 of the depression 80. A flap 85 fixed to the under 65 surface of the head of the shank iron as by rivets passed through the holes 86 and also by a suitable adhesive covers the portion of the pad 23 not received within the depression 80. The flap 85 is usually secured to the covering fabric 70 24 by adhesive, to assist in holding the iron in place.

The shoe is now completed in any well known and desired manner to provide it with an outer sole 90 which, as is clearly shown in Figs. 7 and 75

13, bears upon the flap 85 carried by the head of the shank iron.

It will be noted that, as indicated by the arrow 91 in Fig. 13, the pressure of the pad 23 against 5 that portion of the insole below the metatarsal arch of the foot acts in a forward upward direction. This direction is due to the fact that the apex 48 of the upper portion of the pad, by which pressure is applied to the insole at the apex 10 38 and thence to the arch, is located ahead of the apex 58 of the lower portion of the pad which receives the pressure set up by the shank iron. It will be also noted that the apex 58 is materially 15 in advance of the rear edges of the upper portion 15 of the pad, and that such edges are supported by the body of the shank iron in the rear of the pressure exerting head thereof. These edges and the plane surface 60 of the upper portion of the pad are thus held firmly in position in the insole, 20 and since they do not directly transmit pressure to the arch, there is not only no tendency for them to shift in the depression but, also due to the relative thinness of these parts, they remain firmly in contact with the under surface of the 25 insole and resist any forward pressure of the foot tending to break down the elevation 25 of the insole.

We claim:

1. A shoe bottom structure comprising an insole, a metatarsal pad and a shank iron, said pad having an upper and a lower portion each portion having an apex in its exposed surface, said insole having a depression in which the upper portion of the pad is received and said shank iron having 30 a depression in which the lower portion of the pad is received, the apex of the upper portion being forward of the apex of the lower portion thereby the direction of pressure is forwardly 35 and upwardly through the pad.

2. A shoe bottom structure comprising an insole, a metatarsal pad and a shank iron, said pad having an upper and a lower portion each portion having an apex in its exposed surface, said insole having a depression in which the upper portion 5 of the pad is received and said shank iron having a depression in which the lower portion of the pad is received, the upper portion of the pad being larger than the lower portion and the apex of the lower portion being intermediate the 10 apex of the upper portion and the rear edge thereof.

3. A shoe bottom structure comprising an insole, a metatarsal pad and a shank iron, said pad having an upper and a lower portion each portion 15 having an apex in its exposed surface, said insole having a depression in which the upper portion of the pad is received and said shank iron having a depression in which the lower portion of the pad is received, the upper portion of the pad extending 20 rearwardly of the bottom portion and over the shank iron rearwardly of the depression therein.

4. A metatarsal pad having upper and lower portions, each portion being generally segmental 25 in contour and including a front wall having an arcuate forward edge and a pair of rear walls in angular relation to each, the three said walls being inclined and meeting to define an apex, the apex of the lower portion being intermediate the 30 apex of the upper portion and the rear edge thereof, the upper portion being larger than the lower portion and the forward edges being in contact while the rear edges of the upper portion extend beyond the rear edges of the lower portion. 35
